UNITED STATES PATENT OFFICE.

ELWIN K. HILL, OF CLEVELAND, OHIO.

MACHINE FOR GRANULATING METAL TURNINGS AND BORINGS.

Application filed June 30, 1920. Serial No. 393,103.

To all whom it may concern:

Be it known that I, ELWIN K. HILL, a citizen of the United States, residing at Cleveland, in the county of Cuyahoga and State of Ohio, have invented certain new and useful Improvements in Machines for Granulating Metal Turnings and Borings, of which the following is a specification.

This invention relates to a mill for grinding or reducing to chips the cast-off material resulting from turning or boring metal products, more particularly to a machine for granulating the miscellaneous masses of shavings that issue from a metal turning lathe. The cast-off material from lathes and boring machines, is commonly known as "scrap" and is sold to foundries, to be re-cast. When this material is deposited in the cupola of a furnace, in a loose state, there is a large percentage of waste, as more or less of the material will burn and not fuse. If, however, the material is in a compact mass it will fuse with comparatively small loss. In view of this, means have been provided for compressing this class of "scrap" into extremely compact or substantially solid blocks or billets which when deposited in a furnace, melt substantially the same as solid metal, with a small percentage of loss. As a matter of course this treatment enhances the value of scrap metal of this character. The means devised for this purpose provides powerful presses for forming the loose material into the compact billets, and the feeding of the loose bulk of miscellaneous material to the press has heretofore been a difficult, expensive, and dangerous proposition. The lathe turnings being of spiral ribbon formation, of varying lengths, and different degrees of flexibility and resiliency, and being tangled and intermingled in a miscellaneous bulk, offer stubborn resistance to the loading of the press preparatory to the compressing operation.

The primary object of the present invention is to produce a machine for the treatment of a miscellaneous bulk of scrap metal including turnings, borings and the like, whereby the tangled resilient features are eliminated and the bulk reduced to a docile mass.

In the realization of this main object, I

provide a mill structure embodying feeding mechanism, conveyors, and coacting cutting or shearing elements of novel construction and arrangement, and owing to the character of the material treated, the operating elements are subjected to more or less strenuous usage, therefore a further object of the invention is to provide for the sharpening of the cutting or shearing parts, and the removal and replacement of lining members which become worn.

With these and other apparent objects in view the present invention consists in the construction, combination and arrangement of elements, as hereinafter described and pointed out definitely in the appended claims, reference being had to the accompanying drawings which are made part of the specification, similar characters of reference being employed to designate corresponding parts.

In the drawings Figure 1 is a side elevation of an embodiment of the invention.

Fig. 2 is an end elevation, viewed from the right of Fig. 1.

Fig. 3 is a longitudinal section taken on line 3—3 of Fig. 1. Fig. 4 is a vertical section on line 4—4 of Fig. 2.

Fig. 5 is a fragmentary section on line 5—5 of Fig. 4, with a hood member removed.

Fig. 6 is an inside view of the end plate with a single shearing plate attached.

Fig. 7 is a section on line 7—7 of Fig. 1.

Fig. 8 is an outside view of the end cap, illustrating a modified adjustable attachment of shearing plates, and Fig. 9 is an edge view of said plates.

Fig. 10 is an end elevation of a machine embodying the principles of the invention in a modified form.

It will be understood that the following specification and the drawings associated therewith set forth an embodiment involving the principles of the invention and that in the development of the improved machine I am not confined to this specific construction, various changes in the details, including the general design, proportions, combination and arrangement of parts, and construction of individual members, are allowable without departure from the spirit of the invention or the scope of the claims.

In the simple embodiment, as illustrated, 1 represents the body of the machine or a 5 housing for the operating mechanism. For convenience of assembling, the housing is divided horizontally, the upper member 1^a 10 coacting with the support 1 and forming a chamber 2, and the cap 1^b in conjunction with said support, providing a journal box for the operating shafts 3. A hopper 4 is provided, said hopper being attached to the member 1^a and opening into the chamber 2 through the neck 2^a. The shafts 3 extend longitudinally into the chamber 2, the extended portions 3^a being squared and 15 carrying spiral conveyor members 5. The shafts 3 are simultaneously driven in opposite directions by companion spur gears 50 and 51 which are keyed or otherwise fixed on the operating shafts 3, said gears being actuated by a motor—not shown—through the medium of a pinion 52.

One or more knives 6 are attached to each of the holders 7, said holders being mounted on the members 3^a at the terminals of the 20 conveyors 5, and rotated by said members 3^a. A plate 8, provided with peculiarly shaped openings 8^a which have sharp or shearing edges, is attached to the inner face of a head member 9 which forms the outer 25 end wall of the chamber 2. Said member 9 is provided with openings 9^a that register with the openings 8^a in the shear plate 8. The knives 6 bear on the plate 8, and when rotated they coat with the openings 8^a and 30 perform a shearing function.

Longitudinal lining members 10 arranged circumferentially in the chamber 2 form ridges and depressions, as shown, and coat with the spiral conveyors 5 in forcing and 35 holding the material to the shearing members.

A transverse shaft 11 is mounted in suitable bearings 12 on the outside of the hopper 4. Said shaft is driven by a train of bevel 45 gears 13, 14, 15, 16, 17 and 18, suitably mounted and coacting with the driving gears 50 and 51.

The shaft 11 carries a plurality of radiating arms 11^a, preferably curved as shown. 50 These arms extend into the hopper 4 through a plate 19 provided with slots 19^a. The function of the rotating arms 11^a is to engage the miscellaneous material in the hopper and carry it into the chamber 2 55 where the spiral conveyors 5 receive it. The material is disengaged from the arms 11^a by the plate 19 as said arms recede from said plate through the slots 19^a.

It is desirable that means be provided for 60 adjusting the shearing members to compensate for wear, but as there are various ways of accomplishing this function, I claim this feature broadly, in combination with the other novel elements, in the present application, and to back said claim I have shown

simple operative means for the adjustment of the shearing member 8. This means provides for the interposition of one or more filler plates 20 between the member 8 and the outer cap 9. In the modification shown 70 in Figs. 8 and 9, two shearing plates 80 are employed. Said plates are provided with dowels 80^a which function in seats 9^a in the cap 9, and set screws 21 threaded through the cap 9 bear on the plates 80 and provide 75 for the adjustment of said plates.

Fig. 10 illustrates, in end elevation, a machine in which is embodied a single spiral conveyor. It is not deemed advisable to encumber the present specification with a description of the construction and operation of this embodiment, as it would be merely a repetition of what has already been set forth, with the exception of that part which relates to the coaction of two spiral conveyors. The reference numerals applied to Fig. 10 designate elements that are the equivalent to the elements correspondingly designated in the figures illustrating the double conveyor type.

While I have shown and described an operative mechanism embodying a dual conveyor mechanism, and have mentioned a single conveyor type of machine, it will be understood that, according to the spirit of the invention, and the scope of the claims, there may be a battery of any desired number of conveyors and coacting mechanism varying from that specifically described.

What I claim and desire to secure by Letters Patent is;

1. In a machine for granulating miscellaneous metal shavings, lathe turnings, bittings, and the like, a housing providing a chamber, a spiral conveyor mounted to operate longitudinally in said chamber, longitudinally extending ridges in said chamber in juxtaposition to the outer spiral periphery of the conveyor member, a series of uniformly arranged eccentric openings in the outer end wall of the chamber, cutting blades bearing on the inner face of said end wall, means for conjointly rotating said blades and spiral conveyor so that the edges of the openings in the end wall coat with the blades for shearing the material conveyed to said openings.

2. In a machine for granulating miscellaneous metal shavings, lathe turnings, bittings, and the like, a housing providing a chamber, a plurality of spiral conveyors mounted to operate longitudinally in said chamber, a hopper communicating with said chamber, means for feeding the material to be operated upon to the conveyors, said means operating in the hopper in timed relation to the action of the conveyors, removable lining members within said chamber, said lining members providing longitudinally extending ridges in juxtaposition to

the outer spiral periphery of the conveyors, a closure cap at the outer end of the chamber, said cap being provided with discharge openings, an adjustable plate attached to the interior of said cap, said plate having a series of uniformly arranged eccentric openings therethrough, cutting blades bearing on the inner face of said plate, means for con-

jointly rotating said blades and spiral conveyors so that the blades coact with the edges ¹⁰ of the eccentric openings in the plate for shearing the material conveyed to said openings.

In testimony whereof I affix my signature.

ELWIN K. HILL.
